UNITED STATES PATENT OFFICE

ANTON F. WOLFF, OF GENESEE, IDAHO

TOY AEROPLANE

Application filed February 26, 1930. Serial No. 431,529.

This invention relates to certain new and useful improvements in toys of the rotary ascending and descending aeroplane type.

One of the principal objects of the invention contemplates the provision and arrangement of a supporting apparatus designed to be secured in close proximity to the ceiling of a room to facilitate longer flights at higher altitudes.

Another object of the invention consists of an aeroplane ascending apparatus designed to be automatically released whereby the aeroplanes may descend by their own volition.

More specifically stated the supporting apparatus and aeroplane connections therefor are so constructed that the weight of the planes themselves will be sufficient to impart the rotary motion desired during the different modes of flight.

With the above and other objects in view, the invention further consists of the following novel features and details of construction, to be hereinafter more fully described, illustrated in the accompanying drawings and pointed out in the appended claims.

In the drawings:

Figure 1 is an elevation of the present invention as applied for use showing the automatic ascending apparatus in the act of disengaging itself.

Figure 2 is a top plan view of the invention.

Figure 3 is a vertical sectional view taken on line 3-3 of Figure 1.

Figure 4 is a view similar to Figure 1 with a modified form of my invention.

Figure 5 is a fragmentary elevation of a different form of the invention having a floor support.

Figure 6 is illustrative of certain details of construction.

Figure 7 is a top plan view of a weight supporting bar for the Figure 5 modification.

Figure 8 is a side elevation of a form of weight.

Figure 9 is a top plan view of the aforementioned weight.

Referring to the drawings in detail where-in like characters of reference denote corresponding parts, the reference character 10

indicates a cross arm of bowed formation having the extremities thereof upwardly projected toward the ceiling of a room. A shaft 11 having a hook extremity 12 upon its uppermost end lockingly engaged within the eye 13 of a screw eye or support 14, is journaled at its lowermost end within the central portion of the bowed cross arm 10. A channel member 15 inverted to dispose the bottom thereof flush against the under side of the cross arm 10 and to accommodate the adjacent nut equipped extremity of the shaft 11 carries a pulley wheel 16 upon a pivot pin 17 disposed between the side walls thereof to one side of the vertical center thereof. It will thus be noted from the foregoing description and accompanying drawings that the cross arm and channel member may rotate as a unit independently of and upon the shaft 11. A pin 18, carried by the bottom of the channel member 15 and embedded for an appreciable portion of its length within the immediate surface of the cross arm 10, is designed to prevent distortion of the channel member 15 whereby the pulley wheel 16 will be constantly aligned with that of a companion pulley wheel 19 carried at an appropriate point in the length of the cross arm 10. A double pulley 20 telescopically associated with the shaft 11 and fixed thereon by a cross pin 21 is designed to receive the wrappings of a cord 22 upon the lower pulley section thereof as same is trained over the pulleys 17 and 19.

Pulley wheels 23, constructed after the manner of the aforementioned pulley wheels and disposed within bifurcations in the extremities of the cross arm, train or otherwise direct cords or ropes 24 thereover having connection at their uppermost ends with the upper pulley section of the multiple pulley 20, said cords being wrapped in oppositely disposed relation. Miniature aeroplanes or representations thereof, such as indicated at 25, are carried upon the depending ends of the cords 24 beyond the pulleys 23 in the manner suggested in Figure 1 of the drawings.

From the description thus far, it is understood that the aeroplanes 25 in and of their own weight will descend from the Figure 1

position as the cords 24 are unwound from the upper section of the multiple pulley 20 and swing or otherwise rotate the cross arm 10 in a clockwise direction. During the descending rotary motions of the planes 25, the 5 cord 22 trained over the pulley wheels 16 and 19 respectively will be wound up upon the lower pulley section. The weight 26 carried adjacent the lowermost extremity of the cord 22 is not sufficient in aroirdupois to equal 10 the combined weight of the two planes but will materially restrict progress of flight to such an extent that the rapidity of ascent or descent will be retarded to insure longer flights in both directions.

15 As mentioned previously, it is also my intention to provide a form of plane ascending apparatus which will not only effect such function but which will also become automatically disengaged upon the occasion of 20 the planes having reached the predetermined destination whereby one more flight, that is a descending one, will be effected unaided by the operator of the game. This automatic plane ascending and hook off mechanism primarily resides in the attaching of a ring of 25 the construction shown as at 27 in Figures 1 and 3 of the drawings. The hook off element per se, indicated as at 28, preferably in 30 the formation of a variety of monkey having its tail 29 curved after the manner of a hoop and its two arms extended above its head with both hands clasped together to provide 35 a form of hook 30 for accommodation within in the ring 27. The hands of the monkey are inserted within the ring and hooked thereon when the planes have landed and the cord 22 is wound upon the lower section of the multiple pulley 20. When the monkey is 40 released of the hand of the operator and allowed to descend while the planes are ascending, it is to be noted that the tail 29 upon being brought into engagement with a floor surface or the landing field will rock the monkey 45 and cause same to occupy the Figure 1 position whereby the hands will be released from the ring 27 and the planes will then descend and land. The bowed form of cross arm not only facilitates disposing of the entire apparatus closer to the ceiling whereby longer flights may be made but the respective pulleys will also be aligned to such an extent that the cords may be most effectively wound and rewound.

50 From the vertical sectional view shown in Figure 3 of the drawings, the especial construction of the multiple pulley 20 is exhibited. The characteristic of beads 31 formed upon the inner sides of each of the 55 end flanges of the respective spool sections will serve to prevent the winding of the cords in such manner that same will bind or restrict 60 flight of the aeroplanes.

65 The modified form of my invention disclosed in Figure 4 of the drawings com-

prises essentially the general characteristics of the preferred form and closely follow same in every respect save for the channel member 15. Instead of employing the channel member 15, I make use of the pulley wheel 16 and dispose same within the bowed cross piece 70 in a manner similar to that of the mounting of the pulley wheel 19. A bar, such as indicated at 32, having attaching rings 33 upon its ends and secured to the adjacent extremities of cords 34 oppositely wound upon the lower section of the multiple pulley 20, is also provided with a ring 35 at an intermediate point in the length thereof to facilitate 75 accommodation of the clasped hands of the monkey. The bar 32 is obviously the equivalent in weight to the ball 26 and ring 27 employed in the preferred form.

80 It may be also desirous to provide a form of stand for the apparatus as shown in Figure 5 of the drawings where chandeliers and other lighting fixtures might interfere with the proper functioning of the aeroplanes. Said stand is preferably in the nature of a tube, indicated as at 35, having a floor flange 85 or base 36 secured upon the lowermost end thereof. A pipe section or standard 37 slidably and adjustably mounted within the tube 35 and retained at any desired height by a stop collar 38, including a set screw for the 90 purpose, and seated upon the upper end of the tube 35. A shaft member 39 constructed after the manner of the shaft 11, employed in the other forms of my invention and carrying a similar shape and type of hook 40 upon the 95 uppermost end thereof is rigidly fitted or otherwise connected with the uppermost end of the standard or pipe section 37 through the employment of a bushing 41. The standard 37, bushing and shaft are held as a 100 unitary structure through the employment of a set screw 42 threadedly engaging horizontally of and within the immediate portion of the aforementioned standard.

105 Independent or separate pulleys 43 are 110 arranged and fixedly secured at intervals upon the outer exposed portion of the shaft 39 and upon opposite sides of a cross arm, generally designated as at 45. Bearing or 115 spacing washers 46 loosely connected with the shaft 39 and bearing against the immediate oppositely disposed surfaces of the cross arm and the adjacent ends of the respective pulleys 43 and 44 are designed to permit 120 freedom of movement to the latter mentioned arm.

125 The intermediate portion of the cross arms 45 is upwardly bowed whereby longitudinal passageways 47 in the arm proper may be lined up upon opposite sides of the lowermost pulley 44. Vertical passageways 48 also included in the cross arm have their uppermost ends disposed adjacent the outermost ends of the horizontal passages 47 for 130 purposes to be better understood in the fol-

lowing description of the invention. Cords or flexible connecting elements 49 having their uppermost ends oppositely wound about the core or drum of the lowermost pulley 44 projecting outwardly and downwardly through the passages 47 and 48 in the manner suggested in Figure 5 of the drawings and are subsequently connected terminally thereof with loops 50 formed upon the ends 10 of a weight supporting bar 51. The latter mentioned bar has the loops 50 disposed upon diametrically opposite sides of the tube 35 and it is therefore necessary to provide a semi-circular portion 52 adjacent the middle 15 of the weight supporting bar to skip or otherwise free the tube 35 during the reciprocating actions of the weight supporting bar. A weight member 53, of annular formation, encircling the tube 35 carries hook members 20 54 of the configuration shown designed for detachable connection within the eyes of loops 55 formed adjacent the points of intersection between the horizontal portions of the weight supporting bar 51 and the extremities 25 of the semi-circular portion 52.

The uppermost pulley 43 has the innermost ends of cords or cables 56 oppositely wound thereabout and guided in alignment therewith, incident to the formation of guide 30 recesses 17 within the outermost upwardly and obliquely inclined extremities of the cross arm. Aeroplanes, Zeppelins, gliders and other representations of air craft are to be attached or otherwise suspended from 35 the outermost depending ends of the cords or cables 56 after the manner employed in the previously described forms of my invention.

The invention is susceptible of various 40 changes in its form, proportions and minor details of construction, and the right is herein reserved to make such changes as properly fall within the scope of the appended claims.

45 Having described the invention what is claimed is:

1. A toy comprising a support having upwardly inclined ends, a fixed shaft having the support journaled thereon, pulleys fixed 50 upon said shaft one having cords wound thereon and trained over appropriate portions of the support, toys carried at the outer ends of the cord, a weight equipped cord inversely wound upon the remaining pulley, and a toy 55 elevating element having automatic detachable engagement with the weight equipped cord.

2. A toy comprising a support having upwardly inclined ends, a fixed shaft having 60 the support journaled thereon, pulleys fixed upon said shaft one having cords wound thereon and trained over the support, toys carried at the outer ends of the cords, a weight equipped cord inversely wound upon 65 the remaining pulley, a toy elevating ele-

ment having automatic detachable engagement with the weight equipped cord, and means carried by the support to dispose the weight out of the path of movement of the 70 toys.

3. A toy comprising a support having upwardly inclined ends, a fixed shaft having the support journaled thereon, an anchorage for the shaft having adjustable connection therewith, pulleys fixed upon said shaft one 75 having cords wound thereon and trained over appropriate portions of the support, toys carried at the outer ends of the cords, a weight equipped cord inversely wound upon the remaining pulley, a toy elevating element having automatic detachable connection with the weight equipped cord, and means carried by the support to dispose the weight out of the path of movement of the 80 toys.

In testimony whereof I affix my signature.

ANTON F. WOLFF.
